DESIGN FOR A FLASHLIGHT CASING

Burdon P. Hyde, Naugatuck, Conn., assignor to
Scovill Manufacturing Company, Waterbury,
Conn., a corporation of Connecticut

Application February 9, 1937, Serial No. 67,525

Term of patent 14 years

To all whom it may concern:

Be it known that I, Burdon P. Hyde, a citizen of the United States, residing at Naugatuck, in the county of New Haven and State of Connecticut, have invented a new, original, and ornamental Design for a Flashlight Casing, of which the following is a specification, reference being had to the accompanying drawing, forming part thereof, and in which,—

Figure 1 is a side view of a flashlight casing, embodying my new design.

Figure 2 is a front end view of the same.

Figure 3 is a rear end view of the same.

I claim—

The ornamental design for a flashlight casing substantially as shown.

BURDON P. HYDE.
